[57] ABSTRACT

A device which can be adapted for insertion into a cooling medium for condensing vapors from gaseous streams comprising a tubular container having an inlet tube and outlet tube, a cup member disposed within said container, a coil disposed within said cup member and communicating with said outlet tube and an open ended dip tube which projects through the bottom of said cup member and terminates in said container below said cup member, the purpose of said coil being to pre-cool in-flowing gaseous streams and thereby precondense vapors from such streams, said cup member disposed to catch and retain said precondensed vapors.

CONDENSATE TRAP

BACKGROUND OF THE INVENTION

The invention described herein was made in the course of or under Contract No. AT-33-1-GEN-53 with the United States Atomic Energy Commission.

The invention described herein relates to improvements in apparatus for condensing, freezing out, or otherwise removing condensable vapors from gaseous streams.

Various kinds of process, analytical, and vacuum equipment require the use of cooled condensate traps to remove various unwanted condensable vapors from gaseous streams which may be contained within such equipment. For example, in systems involving the handling of high purity gases, freeze-out traps or more commonly called cold traps, are frequently used to remove such vapors as water vapor, volatile hydrocarbons and other gaseous impurities. High vacuum equipment also often uses condensate traps to remove unwanted vapors from the vacuum system in order to attain ultra low vacuum levels. Also, various instrumentation such as mass spectrometers, helium leak detectors, and other equipment have as a part thereof a cooled condensate trap either for the purpose of attaining low vacuum levels within such instrumentation or for isolating various condensable gaseous constituents for examination. Apparatus for analytical sampling often requires the use of such condensate traps to isolate condensable samples, such as environmental samples from the atmosphere, for analysis.

Various types of condensate traps are well-known in the art and are used for such purposes as gas liquefaction, purification, and separation, condensate collection, and for high vacuum use. For example, a condensate trap by Gaydasch (U.S. Pat. No. 2,659,452) comprises a modification of the standard cold finger type trap modified to eliminate dip tube clogging and thereby increase capacity of the trap. The Gaydasch design incorporates an annular space (dead air space) around a shortened inlet tube to eliminate clogging. A cooled outlet tube which is partially immersed in a coolant is included to ensure efficient freeze out. Similarly, Deaton, et al., (U.S. Pat. No. 3,194,054) incorporates a trap that appears unique in physical configuration for inclusion into the apparatus covered by that patent, but the trap included comprises little more than a coil immersed in a cooling medium.

Condensate traps and the like existing in the prior art suffer from one or more disadvantages which are overcome by the invention described herein. These disadvantages include but are not necessarily limited to: low capacity for condensing and holding impurities in the trap, large size, lack of portability, difficulty of installation and removal from a system of which the trap is a part, or inefficient use of coolant.

SUMMARY OF THE INVENTION

In view of the problems and disadvantages as hereinabove described, it is an object of this invention to provide an improved condensate trap having high capacity.

Another object of this invention is to provide a condensate trap not susceptible to clogging.

Still another object of this invention is to provide a cold trap having a precooling feature for making efficient use of coolant.

It is still another object of this invention to provide a condensate trap having high capacity and which can be easily installed and removed from a system or apparatus incorporating such trap.

These and other objects of the invention described herein will become apparent as the detailed description proceeds.

DESCRIPTION OF THE INVENTION

10 The invention will be more clearly understood from the following detailed description of specific embodiments thereof read in conjunction with accompanying drawing wherein the FIGURE is a cross-sectional view of a preferred embodiment of the condensate trap herein described.

DETAILED DESCRIPTION

One embodiment of the invention described herein is shown in the FIGURE and comprises an elongated generally tubular container 1 having in the upper portion thereof an inlet tube 2 and an outlet tube 3. Cup member 4 is disposed at any suitable position within container 1 and in a spaced relationship to the inner surface of container 1 such as shown in the FIGURE. Inlet tube 2 and outlet tube 3 may, respectively, have disposed at the ends thereof connecting means 5, such as a ball joint, to incorporate the condensate trap into a processing sequence. Tubular coil 6 may be disposed within cup member 4 and communicates with outlet tube 3 and an open ended dip tube 7, which projects through the bottom of cup member 4 and terminates within container 1 below cup member 4.

Inlet tube 2 projects through a wall of container 1 and terminates within cup member 4 near coil 6, and may contain a necked portion 8 in the end thereof within cup member 4.

Port 9, which may be sealable by closure means 10, such as a rubber stopper or ground glass taper, may be provided in container 1 to allow removal of condensed vapors when the condensate trap is not in operation.

In operation, the condensate trap such as shown in the FIGURE may be installed in a larger apparatus or system for the purpose of condensing gaseous impurities from gaseous streams which may be processed in such apparatus or system. The condensate trap may be installed in a generally vertical position such as shown in the FIGURE, thus allowing condensate to accumulate within cup member 4 and container 1, respectively, at the bottom thereof. Coolant may be supplied to the external surface of container 1 in any convenient fashion such as by passing cooled fluids over the surface of container 1 or by inserting container 1 in a cooled bath. Any cooled bath may be used as are well-known in the art, depending on the function and use of the condensate trap within the system of which it is a part, and depending on gas or impurity which is intended to be condensed, and such baths may include such as liquid nitrogen, oxygen, helium, hydrogen, inert gases and other cryogenic fluids, and dry ice, icewater and other coolants.

A gaseous stream which may be processed in a system of which the condensate trap is a part may be allowed to enter the trap, which is cooled as hereinabove described, through inlet tube 2 and necked portion 8, and then circulate over coil 6 into and out of cup member 4 to the bottom of container 1, where the stream is cooled as hereinabove described and certain vapors

are thereby condensed. The gaseous stream, now cooled by contact with the cooled container 1, passes through dip tube 7 and coil 6 and exits the trap through outlet tube 3, and in so passing cools coil 6. Coil 6 is thereby sufficiently cooled so that precondensing of vapors from the gaseous stream entering through inlet tube 2 occurs on coil 6 and the vapors condensed thereby are held within cup member 4. Thus when the gaseous stream reaches the colder lower portion of container 1 sufficient vapors have been removed so that the lower portion of container 1 remains unclogged for extended periods of time, and condensate holding capacity of the trap is increased.

Container 1, cup member 4, coil 6, and the various tubing incorporated within the invention as shown in the FIGURE may be of any convenient size and shape to match the apparatus into which the condensate trap is incorporated so long as the purposes and objects of the invention hereinabove described are met. Similarly, the various component parts may be constructed of quartz or other glasses or of metal, and, therefore, materials of construction of the various component parts is not important so long as the invention functions to precool an incoming gaseous stream to partially remove condensable vapors therefrom and retain such precondensed vapors in a cup-shaped member such as cup member 4. Similarly, the location and configuration of inlet tube 2, outlet tube 3, necked portion 8, coil 6, and port 9 may be varied without departing from the

contemplated scope and spirit of this invention.

Other details of construction of the invention herein described may be applied as might occur to one skilled in the art, and have therefore not been shown in complete detail. Other embodiments may be developed without departing from the spirit and scope of this invention.

What is claimed is:

1. A device for condensing vapors from gaseous streams which comprises an elongated generally tubular container containing an inlet tube and an outlet tube, a cup member disposed within said container in spaced relationship to the inner surface of said container, an open-ended dip tube projecting downward through the bottom of said cup member and terminating within said container beneath said cup member, a tubular coil disposed within said cup member and communicating through one end thereof with said dip tube and through the other end thereof with said outlet tube, said inlet tube projecting through a wall of said container and terminating within said cup member near said coil.
2. The device of claim 1 further comprising a necked portion in the end of said inlet tube within said cup member.
3. The device of claim 1 further comprising a port in said container for removing condensed vapors from said container.
